SUPERHEATER

Carl A. Brandt, Great Neck, N. Y., assignor to
The Superheater Company, New York, N. Y.

Application January 30, 1936, Serial No. 61,495

8 Claims. (Cl. 122—462)

This invention relates to superheaters and more particularly to structures of this kind which are exposed to gases of high temperature for some portions of the superheater and gases of lower temperature for other portions. A situation of this sort is found in the case of locomotive superheaters made up of tubular elements located in the flues. The gases from the firebox passing through the flues are of a very high temperature when they first strike the superheater and are progressively cooler as they flow toward the front end. There has been a steady trend toward higher and higher superheated steam temperatures not only in connection with locomotives but in general superheater use. In the case of a locomotive higher steam temperatures could probably be obtained if more gases were forced through the flues. As it is, those portions of the superheater which lie in the cooler gas zones are not worked anywhere near to the limit of their capacity so that the structure is financially uneconomical. Could the temperature of the gases be raised, as for example by forcing more gases through the flues, the result would be improved from an economical point of view. However, the portions which are nearest to the gas entrance would then be subject to temperatures which they could not resist unless these portions of the superheater elements were made of heat resistant alloy steels, which would in turn introduce a factor of expense.

It is the object of the present invention to provide superheaters, especially of the locomotive type just referred to, which will allow high superheated steam temperatures and yet will not have any of their portions exposed to such conditions that the element would be endangered or that special steels would be required.

In its broader aspects the invention is not limited to locomotive superheaters but has application also to types of superheaters such as used in stationary boilers or in separately fired superheaters, and even to cases where the gases pass over the superheater elements in a direction generally transverse to the tubular portions of the superheater.

The invention will readily be understood from the following description which makes reference to the annexed drawings. Fig. 1 of these drawings is a more or less diagrammatic longitudinal sectional view of one type of locomotive superheater together with the flues in which the elements are located. Figs. 2a and 2b are respectively enlarged lateral views partly in section of certain portions of one of the loops of the super-

heaters shown in Fig. 1; Fig. 3 is a section on line 3—3 of Fig. 2b; Fig. 4 is a view similar to that of Fig. 1 showing, however, only a single flue with another type of superheater element located therein; Figs. 5a and 5b are respectively sections on lines 5a—5a and 5b—5b of Fig. 4. Fig. 6 is a somewhat diagrammatic side elevational view of a superheater of another type; Fig. 7 is a view of a single unit of such a superheater, the section being taken on line 7—7 of Fig. 6.

The superheater element or unit represented in Fig. 1 is of the kind made up of a plurality of loops 1—1 each of which extends into one of the flues 2—2. In this type there is usually only one loop in each flue although the arrangement may be such that each flue may contain more than one loop, the loops in any single flue, however, belonging to different units. The ends of the superheater units are connected to a header 3 with an inlet chamber 4 and an outlet chamber 6. Gases enter the flues 1—1 at the left, as viewed in the figure, and leave at the right.

If in such an arrangement sufficient gases are forced through the flues to result in a desired high final steam temperature, the portions in the vicinity of the entrance end of the gases will be exposed to extremely severe conditions. The gas temperature at this end is very high and the metal temperature will be raised to an inadmissibly high point. The difficulty here is not to get the heat into the metal from the gas, but to carry it away from the metal quickly enough by means of the steam to protect the metallic wall. If means could be provided here to enhance the rate of heat transfer into the steam, then the gas temperature might be allowed to be considerably higher than is admissible in superheaters as built heretofore.

On the other hand, as the outlet ends of the flues are approached, the gas temperature is relatively low and the problem here is not to protect the walls of the elements by carrying away at a high rate the heat delivered to such walls by the gases but to increase the rate at which heat is given up by the gases to the metallic walls.

I satisfy the first named situation by means illustrated in Fig. 2a. The tubular element 1 is here shown in section and it will be noted that on the inside there is placed in each branch of the loop a spiral band 8. This spiral band causes a rotary movement of the steam in addition to the linear movement and this causes a much higher rate of transfer from the walls to

the steam than that obtained with the ordinary unit without such provision.

At the forward end I meet the conditions by securing to the outside of the elements longitudinally extending fins 10-10. See Fig. 2b. These fins increase the rate of heat absorption by the tubes from the gases and so increase the temperature of the walls and hence the transfer from the walls to the steam. As will be seen from Fig. 3, the number of fins is rather optional. One of the branches is shown as provided with three fins whereas the other one is shown with only two. Any desired number of fins may be used and within the scope of my invention the same number may be applied to all the branches or different numbers to different branches.

The outside of that portion of the element which has means on the inside to promote the heat transfer from the metal to the steam is left bare, that is, it is not provided with any means for increasing the rate of heat transfer from the gases to the metal. Similarly the inside of that portion which has means on the outside for enhancing the heat transfer rate is left bare, that is unprovided with any means for increasing the heat transfer means from the metal to the steam.

The flue shown in Figs. 2a and 2b may be any one of the flues of Fig. 1, the arrangement in all of them being similar.

30 By the means described a much higher final superheated steam temperature is obtained than with the ordinary unit and this is done without in any way endangering any portions of the superheater unit by excessive metal temperatures.

35 For a certain length of the unit between the portions near the entrance of the gases and the portions near their exit, conditions for proper rate of heat transfer into and from the metal will be such that either no increase on either side is made or means for the same increase on both sides are provided, the transfer being well balanced over this part of the unit. In the form shown no means are shown either on the inside or on the outside for enhancing the heat trans-
45 fer.

In Figs. 4, 5a and 5b is illustrated a locomotive superheater element of a different type. In this case there are two loops in the flue 2a, both loops belonging to the same superheater element.

50 The invention applies equally well to this case. As seen in Fig. 5a internal means are provided for enhancing the rate of heat transfer from the element wall to the steam in those portions in the vicinity of the gas inlet. In this instance instead of these means taking the form of a spiral as in the case first described, they are here given the form of internal fins extending inwardly from the walls. These fins assist the transfer of the heat from the walls into the steam and 55 perform the same function therefore as the spiral band in the form first described.

At the end of the unit adjacent to the gas outlet of the flues fins are secured to the outside of the tubes assisting the heat transfer from the 60 gases into the tube wall.

This unit will accomplish the same thing that the one first described accomplishes, namely it will make it possible to deliver steam with a higher temperature than is possible with the ordinary unit without thereby endangering the unit at any point by excessive metal temperatures.

The use of the inventive idea is as stated above not limited to locomotive superheater elements, 70 but may be extended to superheaters in station-

ary boilers as well as to separately fired superheaters. An installation of this type is illustrated in Figs. 6 and 7. The heating gases in Fig. 6 flow in an upward direction through the passage defined by the two walls 12-12. Evidently the lower portions of the superheater will be exposed to a higher temperature than those nearer the top. The latter portions are ordinarily not worked up to capacity because to do so would endanger the ones nearer the bottom. In accordance with my invention I enhance the rate of heat transfer from the wall of the element to the steam in those portions adjacent to the gas inlets and enhance the rate of heat transfer from the gases to the element wall for those portions adjacent to the outlet. In the form shown in Fig. 7 the means to accomplish the first of these ends takes the form of fins 8b-8b. The means to increase the heat transfer from the gases to the element in the cooler zones are external 15 fins 10b.

In this form of the invention a further idea is illustrated, namely that the means to aid the heat transfer may be varied so as to result in greater effect in one portion than in another. 25 For example, the internal fins in the lowest two tube lengths are three in number whereas those in the next two tubes are two in number. This illustrates that the increase of transfer from wall to steam may be made greater as the hottest 30 zone is approached.

Similarly, the rate of heat transfer from the gases to the walls of the element may be progressively increased as the cooler zone is approached. 35 This is illustrated by the fact that the third tube from the top in Fig. 7 has two fins, the second one from the top three, and the topmost one four.

A similar progressive increase can be secured in the case of the locomotive units by varying 40 the number or size of the fins as the hotter or cooler zone is approached.

In practicing this invention no doubt variations from the precise forms will occur. As long as they are within the spirit of the invention 45 the following claims are intended to include such variations.

What I claim is:

1. In a steam superheater of the type comprising tubular elements through which the steam flows and portions of which are exposed to heating gases of higher temperature than other portions, the combination of such tubular elements, means within the first named portions to enhance the rate of transfer of heat from the metal 50 to the steam, the outside of the tubes of these portions being bare and means on the outside of the second named portions to enhance the rate of transfer of heat from the gases to the metal, the inside of the tubes of these portions 55 being bare.

2. In a steam superheater of the type comprising tubular elements through which the steam flows and which are exposed to heating gases of progressively higher temperatures from one end 60 of the superheater to the other, the combination of such a superheater with means within those superheater portions exposed to the hotter gases to enhance the rate of heat transfer from the metal to the steam, said means being such 65 and being so arranged that their effect progressively increases as the zone of highest gas temperature is approached, and means on the outside of those portions exposed to the cooler gases to enhance the heat transfer from the 70

gases to the metal, these last-named means being such and so arranged that their effect progressively increases as the zone of lowest gas temperature is approached.

3. In a steam superheater of the type comprising tubular elements located in flues through which the heating gases flow, the combination with such tubular elements of means within those portions of the elements toward the end where the gases enter the flues to enhance the rate of transfer of heat from the metal to the steam, the outside of the tubes of these portions being bare and of means on the outside of those portions of the elements toward the end where the gases leave the flues to enhance the rate of transfer of heat from the gases to the metal, the

inside of the tubes of these portions being bare.

4. Apparatus in accordance with claim 3, at least one of said means being fins.

5. Apparatus in accordance with claim 3, the first-named means being spiral bands.

6. Apparatus in accordance with claim 3, both of said means being fins secured to the tube walls.

7. Apparatus in accordance with claim 3, the first-named means being spiral bands, and the second named means being fins.

8. Apparatus in accordance with claim 3, the first-named means being such as to give a rotary movement to the steam, and the second-named means being fins parallel to the axis of the tube.
